LOCKABLE LOOP HASP

Albert J. Komenak, Stamford, Conn., assignor to
 The Excelsior Hardware Company, Stamford,
 Conn., a corporation of Connecticut

Application August 1, 1940, Serial No. 349,339

11 Claims. (Cl. 70—76)

This invention relates to locks and hasps especially of a type suited for fastening the lids of trunks and articles of luggage, and particularly of a construction employing a loop form of hasp member.

One object of the invention is to prevent the release of a loop form of hasp member from engagement with a draw shoulder by the use of a lock which is located in a manner to be straddled by the arms of the hasp member particularly where the hasp member is materially thinner than the depth of the lock case and it is desired to cover and conceal the bolt of the lock.

Another object is to avoid the necessity for providing a keeper separate from the parts which constitute the hasp structure for engaging with the bolt of the lock.

A further object is to arrange all parts of the combined hasp and lock structures so that the front faces thereof shall come into approximately flush relationship thereby to provide a smooth exterior for the assembled structure free from projections which might catch and tear clothing or injure the user's hands.

A still further object is to arrange the aforesaid parts in an assembled unit which shall be as thin as possible and to produce nearly all of the parts from sheet metal by operations of stamping, bending or drawing thereby to lower the cost of production.

The foregoing and other objectives are referred to in greater particular in the following description of an illustrative embodiment of the invention in which reference is had to the accompanying drawings wherein:

Fig. 1 is a front view of a complete lockable loop hasp in closed and partly locked position, embodying the present improvements.

Fig. 2 is an edgewise view looking upward at Fig. 1.

Fig. 3 is a view taken in section on the plane 3—3 in Fig. 1 looking in the direction of the arrows.

Fig. 4 is a view similar to Fig. 1 with the hasp member and the front wall of the lock housing partly broken away exposing parts of the lock mechanism in unlocked position.

Fig. 5 is a view taken in cross section on the plane 5—5 in Fig. 4 looking in the direction of the arrows.

Fig. 6 is a view similar to Fig. 4 showing the lock parts in locking position and showing the front wall of the hinge housing broken away to expose the detent parts therewithin.

Fig. 7 is a perspective view of the hasp member detached.

Fig. 8 is a perspective view of the housing in which the hasp member is hinged.

5 Fig. 9 is a perspective view of the mounting plate for the cap of Fig. 8.

Fig. 10 is a perspective view of the mounting plate for the lock.

10 Fig. 11 is a perspective view of the lock housing detached from the mounting plate of Fig. 10.

Fig. 12 is a perspective view of the lock bolt.

Fig. 13 is a perspective view of the detent of the lock mechanism.

15 Fig. 14 is a perspective view of the key barrel of the lock.

Fig. 15 is a view looking at the rear end of the key barrel of Fig. 14.

The parts of Figs. 7 to 14, inclusive, comprise all of the parts that are necessary to be 20 assembled to form a complete lock and hasp structure incorporating the present improvements. The hinge abutment, illustrated herein in the form of housing 10 is provided with tongues 11 which project through slots 12 in the

25 mounting plate 13 and sufficiently therebeyond to have their extremities swaged or peened over permanently to hold parts 10 and 13 together. By this means the hinge bar 14 of the loop-like hasp member 16 is pivotally anchored at the front or rounded, closed end 17 of notches 18 in the side walls of housing 10, being yieldingly pressed thereagainst by the two leaf springs 19 which are secured by rivets 21 to the mounting plate

30 13 which is adapted to abut flatly against the front surface of the lid of a trunk or the like to which it may be secured as hereinafter referred to.

35 Hinge bar 14 of the hasp member carries a lug 24 for cooperating with springs 19 to effect a detent action and this lug may be formed by the

shape to which the hasp member is blanked out of sheet metal, the portions 25 of the hinge bar 14 being swaged into a round cross sectional

40 shape for affording a smoother pivot for the hasp member within the notches 18. The nose portion of the hasp member is preferably thinner than the depth of the lock case by an amount at least equal to the thickness of a lock bolt 38 hereinafter more fully referred to and includes a carried block-like section 26 backed by the

45 notch 27 which receives this lock bolt so that the latter is covered and concealed by said block-like section of the nose portion of the hasp member. The block-like section 26 may be spot welded or otherwise mounted on and made rigid

with the hasp loop, or in case the loop is formed by a die casting, may be an integral part of the metal thereof. The rear edge of the nose of the hasp loop is chamfered at 30 to facilitate entrance of the fingers therebehind for pulling forward and lifting the loop. The rearwardly extending lug 28 constitutes a keeper structure providing a shoulder which flanks notch 27 at the rear thereof and which is engageable by the lock bolt 38 being offset to the rear of the total thickness of the hasp member as well as offset to the rear of the total depth of lock case 32 in Fig. 3. Lug 28 is received into a square aperture 29 in the mounting plate 31 for the lock case 32. The latter has tongues 33 which enter and fit slots 34 in the mounting plate 31 and project at the rear thereof sufficiently to be swaged or peaned over to hold the lock case 32 and mounting plate 31 permanently together. The lock case 32 is notched at 36 to accommodate the nose section 26 on the hasp loop so that the frontmost face 37 of the keeper block 26 may fall approximately flush with the front surface of the lock case.

Contained within the lock case are the working parts of the lock mechanism including the plate-like bolt 38, the pawl 64 and the key barrel 41 shown respectively in Figs. 12, 13, and 14. The bolt plate 38 has an elongated aperture 42 through which extends the key barrel 41, the latter being journaled by means of its end 43 of reduced diameter in a hole 44 in mounting plate 31. The front end 46 of the key barrel is journaled in the key-hole 48 in the front wall 49 of lock case 32 and the key barrel as a whole is retained by its flange 51 which occupies a counterbore 47 in said front wall of the lock case at the rear of the keyhole. In usual fashion the key (not shown) is inserted through keyhole 48 and through the configured slot 52, its working edge engaging the notch 53 in bolt plate 38. The latter has an elongated slot 54 and an elongated notch 56 in line therewith each respectively engaged and guided by the short pin 57 and the long pin 58 which are fixedly mounted on plate 31. This plate contains at its top edge a recess 59 to receive the dowel tongue 22 which enters thereinto back of the edge 61 of the lock case which flatly abuts against the front surface of mounting plate 31.

The bolt plate 38 also carries the lug 62 which cooperates with a finger 63 projecting from pawl 64, the latter being loosely pivoted on long stud 58 by means of its hole 66. The concave portion 67 of the edge of pawl 64 is adapted for coaction with the working edge of the key. In the heel 68 of pawl 64 is tightly anchored one end 69 of a leaf spring 71 whose free end bears against the inside surface of the edge wall 72 of the lock case constantly causing pawl 64 to be urged counter-clockwise or toward the bolt lug in Figs. 4 and 6. Two holes 73 in mounting plate 13 and three holes 74 in mounting plate 31 accommodate screws or rivets (not shown) for fastening these plates interchangeably and respectively to the cover and body of a trunk or other piece of luggage.

In operation, the lid of the trunk or other piece of baggage carrying plate 13 is closed against the body of the trunk in the usual way whereupon dowel tongue 22 enters recess 59 thus accurately aligning the side walls of the hinge case 10 and lock case 32, so that the hasp member 16 may be swung downward from its position in Fig. 5 to its position in Fig. 1. This presents the keeper notch 27 to the lock bolt 38 which may then be shot into engagement with the keeper 28 by turning a key in barrel 41 thus shifting the parts from their

positions in Fig. 4 to their positions in Fig. 6. This, by concealed means inaccessible except by use of the key, makes it impossible to swing hasp member 16 away from the position in which its 5 arms straddle lock case 32 and detains the curved nose of the hasp member engaged with its draw shoulder formed by the correspondingly curved bottom end of the lock case. The parts present a flush and smooth appearance when thus locked, 10 the front portion of keeper block 26 nicely filling the lock case opening 36. This is in part made possible by the described relative dispositions and dimensional relationships of lock case 32, lock bolt 38, hasp nose section 26 and keeper structure 28. 15 Some of the advantages of these improvements may be obtained by the use of parts differing from those herein disclosed in shape and arrangement, as for instance the loop-like hasp member may be swung from a toggle action lever capable of causing 20 the nose loop of the hasp member to draw very tightly against its draw shoulder, and such toggle action lever, instead of the hasp member itself, may be engaged by the lock bolt and thereby prevented from swinging open. Also the draw 25 shoulder may be comprised of a part separable from the lock case. These and other departures from the preferred embodiment herein disclosed, together with all fair equivalents which come within the definitions of the appended claims, are 30 intended to be included and covered within the scope of the claims.

I claim:

1. In a lockable hasp fastener including a lock case and a hinge abutment separable therefrom, the combination with said case and abutment of, a loop-like hasp member having a nose portion bordering said case carried by spaced arms pivotally connected to said abutment and swingable to a position in which said arms straddle said lock case when the latter is close to said abutment, keeper structure carried by said nose portion of the hasp member offset therefrom to the rear of said lock case when said arms straddle the latter and providing a striker shoulder, and a bolt within 35 said lock case constructed and arranged to be shot therefrom into locking engagement with said striker shoulder between the latter and said nose portion of the hasp member thereby to be covered and concealed by said nose portion when said hasp member arms straddle said lock case, said nose portion of the hasp member being thinner than the depth of said lock case from front to rear by an amount at least equalling the thickness of said bolt.
2. In a lockable hasp fastener including a lock case and a hinge abutment separable therefrom, the combination with said case and abutment of, a loop-like hasp member having a nose portion in part thinner from front to rear than the depth 40 of said lock case bordering the latter and carried by spaced arms pivotally connected to said abutment and swingable to a position in which said arms straddle said lock case when the latter is close to said abutment, keeper structure carried by said thin nose portion of the hasp member forming a hollow which opens toward said lock case and is bordered by a striker shoulder offset rearwardly with respect to said nose portion, and a bolt within said lock case constructed and arranged to be shot therefrom into said hollow and into locking engagement with said striker shoulder in a manner to be covered and concealed by said keeper structure when said hasp member arms straddle said lock case.
3. A lock comprising in combination with a bolt 45

mechanism, an escutcheon plate, a cap-like case having front and side walls assembled edgewise with said plate in a manner to house said bolt mechanism, a niche formed in said case by cutting away portions of its said front and edge walls, and a bolt within said case operable by said mechanism in a manner to project into and withdraw from said niche.

4. A lock as defined in claim 3 in which the said escutcheon plate contains an aperture registering and communicating with the said niche thereby to permit a striker passing through said niche to enter said aperture and lie behind the said bolt.

5. In a lockable hasp fastener including a lock case containing a recess at one end thereof and a hinge abutment separable from the opposite end of said lock case, the combination with said lock case and hinge abutment, of a loop-like hasp member having a nose portion carried by spaced arms pivotally connected to said abutment to be swingable to a position in which said arms straddle said lock case when the latter is close to said abutment, a keeper carried by and projecting from said nose portion of the hasp member in a manner to enter and occupy said recess when said arms of the hasp member are positioned to straddle the lock case, and a bolt within said lock case constructed and arranged to be shot therefrom into locking engagement with said keeper.

6. In a lockable hasp fastener including a lock case containing a recess and a hinge abutment separable therefrom, the combination of, a loop-like hasp member having a nose portion carried by spaced arms pivotally anchored to said abutment to be swingable to a position in which said arms straddle said lock case when the latter is close to said abutment, a keeper carried by and projecting from said nose portion of the hasp member in a manner to enter said recess having a shape and size to fit and fill said recess thereby to render the latter inconspicuous when said arms of the hasp member are positioned to straddle the lock case, and a bolt within said lock case constructed and arranged to be shot therefrom into locking engagement with said keeper.

7. In a lockable hasp fastener including a lock case and a hinge abutment separable therefrom, the combination with said case and abutment, of a loop-like hasp member having a nose portion

carried by spaced arms pivotally connected to said abutment to be swingable to a position in which said arms straddle said lock case when the latter is close to said abutment, a keeper carried by said nose portion of the hasp member, and a bolt within said lock case constructed and arranged to be shot therefrom into locking engagement with said keeper, together with an escutcheon plate underlying said lock case, the said lock case and the said escutcheon plate being cut away to form a common recess and the said keeper projecting from said nose portion of the hasp member in a manner to enter and occupy said recess when said arms of the hasp member are positioned to straddle the lock case.

8. In a lockable hasp fastening, a lock case comprising a hollow structure forming an open chamber bordered by the free edges of its walls and a mounting plate at the rear of said structure assembled against said free edges of said walls and closing said chamber, and a dowel tongue separable from said lock case, said plate containing a recess cut thereinto from one of its edges and underlying one of said free edges of the case walls thereby to receive and constrain said dowel tongue within the plane of said plate and at the rear of said lock case.

9. Spring hinge structure for anchoring and biasing a swingable U-shaped hasp member, including in combination, a hinge bar joining the side arms of said hasp member and bridging the space therebetween, a hollow housing occupying said space between the arms having apertured walls affording pivotal bearings for said hinge bar and a leaf spring mounted to operate within said housing shaped and engaging cooperatively with said bar in a manner to bias said hasp member into either of two positions in which two positions said hasp arms extend respectively upward and downward from said hinge bar.

10. Spring hinge structure as defined in claim 9 in which the said hinge bar is relatively thin and possesses flat opposite faces alternately engageable by the said leaf spring.

11. Spring hinge structure as defined in claim 9, in which the said pivotal bearings for the said hinge bar are formed by notches opening at one end through the edges of said walls, and the said leaf spring urges said hinge bar against the opposite blind ends of said notches.

ALBERT J. KOMENAK.
